UNITED STATES PATENT OFFICE.

WILLIAM H. L. WOOD, OF MANCHESTER, ENGLAND, ASSIGNOR TO WESTINGHOUSE ELECTRIC & MANUFACTURING CO., A CORPORATION OF PENNSYLVANIA.

TERMINAL FOR ELECTRICAL MEASURING INSTRUMENTS.

Application filed June 25, 1920, Serial No. 391,749, and in England June 27, 1919.

My invention relates to the insulation of the leads passing through the cases of electrical measuring instruments and the like and is especially applicable to those instruments which are intended to be attached to a switchboard or panel where it is necessary to make provision for passing leads or rods through the panel and through the back of the instrument case into the interior thereof in order to make the necessary electrical connections.

The object of my invention is to provide an improved terminal for electrical measuring instruments.

It has hitherto been the practice to provide for insulating the leads or rods, where they extend through the case of an instrument, by means of a bushing of hard rubber or other suitable insulating material that is provided with a flange and that may be secured by screws extending through the flange into the instrument case. It has also been a common practice to provide such bushing with an internal sleeve of brass having a square flange embedded in the bushing, the interior of which sleeve is so screw-threaded that a terminal post may be screwed thereinto from the inside of the instrument and a rod, which extends through the panel of the switchboard, may be screwed into the other end of the sleeve, thus enabling a connection to be made through the switchboard to the instrument terminals. It has been found, however, that considerable strain is placed upon the insulating bushing when the rods are screwed up, thus tending to burst the insulation or to tear it away from the screws by which it is secured to the instrument case, and the size of the bushing has, therefore, been increased in order to enable it to withstand the strain. Breakage is also liable to occur if any pressure is accidentally applied to the rear connections.

In practicing my invention, I provide an insulating bushing of a size that is no larger than is necessary to properly insulate the lead or rod extending through it, but, in order to prevent damage to the bushing, as hereinabove described, I further provide a re-enforcing means comprising an enclosing cap of metal that may be secured to the instrument case by screws that are adapted

to extend through the cap or through lugs attached thereto.

In order that the nature of the invention may be clearly understood, it will now be described with reference to the accompanying drawing in which

Figure 1 is a front elevational view of a terminal embodying my invention; and Fig. 2 is a side view, partially in elevation and partially in section, of the terminal shown in Fig. 1.

Referring to the drawings, the terminal comprises a bushing 2 of suitable insulating material that does not require great mechanical strength but must be able to resist a certain amount of compression. The bushing 2 is provided with a flange 3, the perimeter of which is of substantially polygonal or irregular shape, that is enclosed, except on the side that is to be applied to the case 4 of the instrument, by a closely-fitting cap 5 of brass or other suitable sheet metal. The bushing 2 projects through the plane face of the cap 5 and surrounds an internally threaded brass sleeve 6 that has a square, polygonal or irregular flange 7 into which a threaded rod 8, forming the internal terminal of the instrument, may be threaded. A rod 9, that is adapted to extend through the panel 10, may be threaded into the opposite end of the sleeve 6. Since flange 7 projects laterally into the bushing 2 in which it is embedded, it is prevented from being pulled or pushed out of the bushing and, since it is provided with a polygonal or irregular perimeter, it is prevented from rotating therein.

The terminal may be secured to the case 4 of the instrument by means of a plurality of screws 11 that extend through openings in the plane face of the cap 5 and through openings in the bushing 2 that are preferably slightly larger than the openings in the cap or by means of screws that extend through lugs that may be provided projecting from the sides of the cap.

The terminal may preferably be disposed within the instrument case since, if it were attached on the outside thereof, it could be removed and the usual sealing of the instrument cover rendered useless.

It will be seen that, with the improved construction, any tendency to break the in-

sulating bushing by turning the metal sleeve or the rods screwed thereinto will be prevented because the breaking strain will be transmitted by the irregular perimeter of the flange 7 to the sides of the enclosing cap and, from the cap to the case 4 through the screws 11. The insulating material will merely be placed in compression between the flange 7 and the sides of the cap 2.

10 While I have shown a preferred form of terminal embodying my invention, I do not limit it to the specific structure shown as various modifications may be made therein within the spirit and scope of the invention 15 as set forth in the appended claims.

I claim as my invention:

1. In a terminal, the combination with a base member, of an insulating member having a portion outside said base member, a conductor in said insulating member subject to turning forces, and a reinforcing member for said outside portion secured to said base member, said conductor and reinforcing member having portions co-operating in response to said turning forces to place said insulating member in compression, and to widely distribute said forces in the insulating member, between them.

2. In a terminal, the combination with a base member, of an insulating member having a portion outside said base member, a conductor in said insulating member subject to turning forces, and a reinforcing jacket surrounding said outside portion and secured to said base member, said conductor and jacket having portions co-operating in response to said turning forces to place said insulating member in compression, and to widely distribute said forces in the insulating member, between them.

3. In a terminal, the combination with a base member, of an insulating member having a portion outside said base member, a conductor in said insulating member subject to turning forces, a relatively thin sheet-metal reinforcing jacket surrounding said outside portion, and means co-operating with the jacket for securing the insulating member to the base member, said conductor and jacket having portions co-operating in response to said turning forces to place said insulating member in compression, and to widely distribute said forces in the insulating member, between them.

4. In a terminal, the combination with a base member, of an insulating member having a portion outside said base member, a conductor in said insulating member subject

to turning forces, a relatively thin sheet-metal reinforcing jacket of substantially 60 cup-shape surrounding said outside portion, and means co-operating with the jacket free of the insulating member for securing the latter to the base member, said conductor and jacket having portions co-operating in 65 response to said turning forces to place said insulating member in compression, and to widely distribute said forces in the insulating member, between them.

5. In a terminal, the combination with a 70 base member, of an insulating member having a portion outside said base member, a conductor in said insulating member subject to turning forces, a relatively thin sheet-metal reinforcing jacket of substantially 75 cup-shape surrounding said outside portion, and screws extending through the outer wall of the jacket and through the insulating member free of the latter for securing the same to the base member, said conductor 80 and jacket having portions co-operating in response to said turning forces to place said insulating member in compression and to widely distribute said forces in the insulating member between them.

6. In a terminal, the combination with a base member having an opening therethrough, of an insulating bushing having a portion in said opening and a portion outside the same, a conductor in said bushing subject to turning forces and a reinforcing jacket for said outside portion of the bushing secured to said base plate, said conductor and jacket having portions co-operating in response to said turning forces to place said bushing in compression, and to widely distribute said forces in the bushing, between them.

7. In a terminal, the combination with a base member, of an insulating member having a polygonal portion outside said base member, a conductor in said insulating member having a polygonal portion subject to turning forces in said outside portion thereof, and a reinforcing jacket enclosing, 105 and conforming to, said polygonal outside portion of the insulating member and secured to said base member, said polygonal portions co-operating to prevent damage to the insulating member by placing portions 110 of the latter in relatively broad flat compression between them.

In testimony whereof, I have hereunto subscribed my name this first day of June, 1920.

WILLIAM H. L. WOOD.
